CLAIM

The ornamental design for an all-directional seismic (restraint) spring mount with housing, as shown and described.

DESCRIPTION

FIG. 1. is a front view of the all-directional seismic (restraint) spring mount with housing;

FIG. 2. is a rear view thereof;

FIG. 3. is a side view thereof;

FIG. 4. is a top view thereof;

FIG. 5. is a bottom view thereof;

FIG. 6. is a perspective front and side view thereof;

FIG. 7. is a perspective rear and side view thereof; and,

FIG. 8. is a disassembled front and side view thereof.

1 Claim, 2 Drawing Sheets
